UNITED STATES PATENT OFFICE

157,265

COMBINED VANITY CASE AND LIPSTICK
HOLDER

Sol Kaufman, New York, N. Y.

Application March 22, 1948, Serial No. 145,259

Term of patent 7 years

(Cl. D86—10)

To all whom it may concern:

Be it known that I, Sol Kaufman, a citizen of the United States, residing at New York city, in the county and State of New York, have invented a new, original, and ornamental Design for a Combined Vanity Case and Lipstick Holder, of which the following is a specification, reference being had to the accompanying drawing, forming a part thereof.

Fig. 1 is a top plan view of a combined vanity case and lipstick holder, showing my new design.

Fig. 2 is a rear view thereof.

Fig. 3 is a side view thereof.

Fig. 4 is a bottom plan view thereof.

Fig. 5 is a top plan view thereof shown in open condition.

Fig. 6 is a partially exploded view of the combined vanity case and lipstick holder in open condition with the lipstick case raised from its cradle.

I claim:

The ornamental design for a combined vanity case and lipstick holder, substantially as shown.

SOL KAUFMAN.
